UNITED STATES PATENT OFFICE.

MORRIS MOSKOWITZ, OF NEW YORK, N. Y., ASSIGNOR TO THE UNITED STATES LIGHT & HEATING COMPANY, OF NEW YORK, N. Y., A CORPORATION OF NEW JERSEY.

ELECTRIC REGULATION.

No. 893,936.

Specification of Letters Patent.

Patented July 21, 1908.

Application filed April 2, 1906. Serial No. 309,315.

To all whom it may concern:

Be it known that I, MORRIS MOSKOWITZ, a citizen of the United States, and resident of the borough of Brooklyn, county of Kings, city and State of New York, have invented certain new and useful Improvements in Electric Regulation, of which the following is a specification accompanied by drawings.

This invention relates to means for regulating electric circuits, more particularly electric lamp circuits when using a constant current machine and a storage battery in multiple.

When a constant current generator is used to charge a secondary battery with a given amperage, and lamps are fed from the machine at the same time, there is a variation in voltage due to the counter electro-motive force of the storage battery. If the lamps draw the full amount of current supplied by the generator, and the battery is only floating on the line, the lamps will receive a voltage equal to that of the battery only. If the lamps are all turned off but one, and all the current less than that to supply the one lamp is forced through the battery, the voltage across the brushes of the generator will rise enormously, which means destruction to the lamp. If only half of the lamps are turned off the difference in voltage will not be so great, but will still be too high for the lamps. Since the commercial incandescent lamp is burning just below the point of destruction, it is evident that an increase of voltage will materially shorten the life of the lamp.

The objects of the present invention are to improve upon the construction and operation of means for regulating circuits of the character described and increase the certainty and efficiency of operation of such regulating means.

Another object is to automatically prevent the rheostat from affecting the battery when supplying current to the load.

Further objects of the invention will hereinafter appear and to these ends the invention consists of apparatus for carrying out the above objects embodying the features of construction, combinations of elements, and arrangement of parts having the general mode of operation substantially as herein-after fully described and claimed in this specification, and shown in the accompanying drawings, in which the figure is a diagram-

matic representation of circuits and apparatus for carrying out the invention.

Referring to the drawings A represents a suitable constant current generator which may be driven from any suitable source of power, as for instance, an engine, or from the axle of a car if the apparatus is to be used for car lighting.

B represents a storage battery connected in parallel with the generator A, and C represents the work circuit in which the load consists of the lamps D although other translating devices may be inserted in the work circuit.

E represents a suitable rheostat comprising the contacts F and resistance G inserted in series with the work circuit C.

A device for regulating the generator circuit is shown in the form of a rheostat, but any other suitable regulating means may be used. In this instance the rheostat is shown manually operated, the arm H being adapted to be moved over the contacts as by means of the handle I, and preferably the arm is provided with a pointer J which moves over an indicating scale K for indicating the required position of the rheostat arm with a given load on the work circuit.

Means are provided for preventing the regulating device or rheostat from affecting the battery when the battery is supplying the work circuit, and preferably automatic means are provided for accomplishing this object. Any suitable circuits and connections may be provided for preventing the rheostat from affecting the battery when the battery is supplying current, in this instance a rheostat being shunted by the automatic device L shown, preferably as an electromagnetic switch.

From the positive pole of the generator A a wire 1 leads to a switch contact 2, and from an adjacent switch contact 3 a wire 2^a leads to the electro magnets O and P of the automatic regulator L. From thence a wire 3^a leads to the positive pole 4 of the battery B. From the point 5 on the wire 3^a a connection 6 leads to the contact arm H of the rheostat and from one end 7 of the resistance G, wire 8 leads to one contact 9 of a switch 10, which switch is provided with another contact 11 connected to the armature 12, controlled by the electro magnets O and P. The other end of the armature 12 is connected by a wire 13

with the point 14 on the wire 3^a adjacent the magnet P. The armature 12 is provided with retracting means, in this instance in the form of a weight W.

5 From the contact 9 a wire 15 connects with one side of the work circuit, the other side of which is connected to the point 16 on the wire 17, which connects the negative pole of the battery with the wire 18 leading to the 10 negative pole of the generator.

The magnets O and P are compound wound, one winding as shown being in series with the generator circuit and the other winding on each magnet being in a shunt circuit which leads from the point 19 on the wire 1 adjacent the switch contacts 2 and 3, to the magnets O and P by wire 2^c and thence by wire 20 to the point 21 on the wire 18.

In the operation of the circuits and apparatus disclosed, when the generator A is supplying current to the work circuit C, the windings on the magnets O and P act cumulatively and attract the armature 12, thereby closing the circuit at the switch contacts 2 and 3 by means of the switch blade 22 which bridges said contacts. The current then passes from the positive pole of the generator A by means of wire 1 to and through the switch contacts 2 and 3, thence by wire 2^a through the series windings on magnets O and P, thence by wire 3^a to the point 5, by wire 6 through arm H, a portion of resistance G, by wire 8 to switch contact 9 and the circuit being broken at contacts 9 and 11, the 35 current continues by wire 15 to and through the work circuit, and thence by wire 18 to the negative brush of the generator A. The shunt windings on the magnets O and P are also energized by current passing from the 40 point 19 on wire 1, by wire 20 to and through said shunt windings, and thence back to the negative side of the generator A by wire 20.

When the battery B is supplying current to the work circuit the windings on the magnets O and P act differentially and thereby permit the weight W to retract the armature 12 which opens the circuit at the contacts 2 and 3, and closes the circuit between the contacts 9 and 11 of switch 10. Current 50 then passes from the positive pole of the battery B to the point 5, thence through the shunt circuit provided by wire 3^a to the point 14 adjacent the magnet P, and thence by wire 13 to and through the armature 12, 55 the switch 10, through said switch which is closed and by wire 15 to the work circuit C and from said work circuit by wire 17 to the negative pole of the battery B. The rheostat E is therefore shunted when the battery 60 is supplying current for the work circuit, and the battery is not affected by the resistance G.

According to this invention it will be seen that the armature 12 forms a switch arm,

and the weight W has the function of a retracting device adapted to move the switch arm 12 in the opposite direction to that in which it is moved by the electro-magnets L. Both shunt and series windings of the electro-magnet L are located on the same side 70 of the switch arm 12, so that the retracting device opposes the action of the magnets. The switch arm 12 is electrically connected to the line between the resistance E and the electro-magnet L. The switch 22 is the 75 main switch in the line between the generator and the electro-magnet, while the switch 10 is the auxiliary switch adapted to connect the battery to the work circuit at a point between the resistance E and the load, 80 thereby short-circuiting the resistance when the battery is supplying the work circuit.

Obviously some features of this invention may be used without others and the invention may be embodied in widely varying 85 forms.

Therefore, without limiting the invention to the devices shown and described, and without enumerating equivalents, I claim and desire to obtain by Letters Patent the following:—

The combination of a work circuit, a main generator feeding said work circuit, a storage battery connected in parallel across the work circuit, a variable resistance in series with the work circuit, an armature forming a switch arm, a compound wound electro-magnet controlling said switch arm, a retracting device adapted to move the switch arm in the opposite direction to that in which it is moved by the electro-magnet, one winding of the magnet being in series with the line, and the other winding being in a shunt circuit, and both windings being located on the same side of the switch arm, said switch arm 95 being electrically connected to the line between the resistance and the electro-magnet, a main switch in the line between the generator and the electro-magnet, and controlled by said switch arm, and an auxiliary 100 switch adapted to connect the battery to the work circuit at a point between the resistance and the load, thereby short-circuiting the resistance when the battery is supplying the work circuit, said series and shunt windings on the electro-magnet acting cumulatively 105 when the generator is supplying the work circuit, and acting differentially when the battery discharges back through the generator.

In testimony whereof I have signed this specification in the presence of two subscribing witnesses.

MORRIS MOSKOWITZ.
